UNITED STATES PATENT OFFICE.

GENEVIEVE H. MYERS, OF OAKLAND, CALIFORNIA, ASSIGNOR OF ONE-HALF TO M. C. FRANK, OF OAKLAND, CALIFORNIA.

FANCY HANDKERCHIEF.

Application filed November 1, 1926. Serial No. 145,434.

My invention relates to handkerchiefs such as are now in vogue for ornamental purposes, and in general to any handkerchief intended to project from a pocket of clothing, purses, or the like, for ornamental effect.

It is an object of my invention to provide a handkerchief which can be adjusted to project from the pocket to produce an effect which artistic persons strive to approximate with ordinary handkerchiefs. It is the object of my invention to provide means by which this effect can be attained more perfectly than has heretofore been possible. It is furthermore an object of my invention to permit this effect to be attained simply, quickly, and by the average person.

It is an object of my invention to provide a handkerchief embodying an ornamental decoration with means for effectively displaying said decoration. It is an object of my invention to produce a handkerchief having a painted design on filmy material with means permitting the design to lie flat while the remainder of the handkerchief is artistically arranged.

It is further an object of my invention to provide means teaching the inventor's preferred mode of wearing the handkerchief.

Other and ancillary objects of my invention will be suggested in the following description of the preferred embodiment thereof, or will be suggested in the use of my improved type of handkerchief. It is to be understood that certain desirable objects of my invention may be attained with the use of less than all its preferred features or with modifications thereof within its purview. I desire therefore not to be circumscribed beyond the limits of the claims finally determining my invention.

Referring to the drawings:

Figure 1 is a small-scale plan representing an unfolded handkerchief embodying my invention. Fig. 2 is a small-scale plan representing the handkerchief of my invention partially folded, to clearly illustrate the character of ornamental flap embodied in the handkerchief. Fig. 3 is a substantially full-scale front elevation of a pocket-like display card with my improved type of handkerchief artistically arranged therein.

It is common form to allow the handkerchief to project beyond the pocket of the garment, purse, or sleeve containing it, for

the ornamental effect produced. Considerable artistry is required to arrange even a plain handkerchief prettily. Where initials or ornamental embroidery on the handkerchief are displayed, the task is more exacting. A current mode dictates handkerchiefs with hand-painted pictures in one corner (see Fig. 3), and these must be arranged to disclose the picture without distortion as well as to produce a pleasing draped or otherwise arranged effect. In the past it has been practically impossible to more than approximate the desired flatness of the design portion in a handkerchief the rest of which is arranged to one's best ability. I attain this desired effect by separating the design-bearing portion 2 from the rest of the handkerchief 4. The portion 2 is formed into an integral flap by two parallel cuts 6—6' and 7—7', one on either side of the corner, and extending inwardly parallel to the diagonal of the rectangular handkerchief.

By this description, from which it will be recognized that I prefer to use a rectangular handkerchief, it must not be assumed that my invention is not applicable to other shapes as well. Square shape is preferable because it involves the least change from the accepted style and because of the nice manner in which the portion 4 of a square handkerchief lends itself to a draped or folded effect about the pocket.

The flap 2 may be trimmed to other shapes than that disclosed; in fact, it might be formed at other than the corner portion of the handkerchief; but I do prefer the illustrated shape and positioning thereof.

I prefer to use a soft filmy material, such as silk, crepe, or fine linen, or any suitable material, for both the flap and the rest of the handkerchief. The filmy character of the material permits the handkerchief to be artistically arranged, and permits the flap to depend from, and conform to the surface of, the pocket from which it projects; and, in the case of painted designs, gives a softness, warmth, and fineness which cannot be attained in other paintings.

The cut edges 6, 6', 7 and 7', may be finished in any desired manner as by hemming, picoting, gilding, or other edging, and will usually be made to harmonize with the edges of the remainder of the handkerchief.

The mode of wearing the handkerchief of

2
my invention will vary somewhat according to personal taste. I teach the preferred mode by displaying each handkerchief for sale, as shown in Fig. 3, on a suitable card 8 having a slit 10 in its surface to correspond to a pocket in clothing, and having a representation 12, of the pocket outline drawn thereupon. The handkerchief is grasped along the diagonal 14 (see Fig. 2) 10 which does not include the flap, and is stuffed into the pocket-like slit 10 with the body portion 4 draped and arranged as shown and projecting above the slit, while the flap 2 is folded down and depends from 15 the opening 10 in conforming relation to the card 8. This type of display teaches one manner in which the handkerchief may be used; it being contemplated that the handkerchief will be inserted into the pocket of 20 a garment or purse or between the arm and a bracelet, in the same manner in which it is inserted into the display card. The display card is, in fact, one form of pocket.

It will be noted that the applicant's invention consists of a handkerchief having slits extending inwardly from the border thereof, so as to provide a flap foldable relatively to the body portion on a line joining the inner ends of the slits. The flap is of such extent 25 determined by the length of the fold line and the characteristics of the material, that when the body portion of the handkerchief is tucked into a pocket with a fold line at 30

the pocket opening and the body portion adjacent the fold line depending from the fold line into the pocket, the flap will depend by reason of its weight alone from the fold line downwardly and will lie smoothly against the outside of the pocket.

40 I claim:

1. A handkerchief comprising a rectangular body portion cut along a pair of lines one on either side of one rectangular corner and substantially parallel to the diagonal through said corner and extending into the body portion to provide a flap as and for the purposes set forth.

45 2. A handkerchief having slits extending inwardly from the border thereof to provide a flap foldable relatively to the body portion on a line joining the inner ends of the slits, said flap being of such extent determined by the length of the fold line and the characteristics of the material that when the body portion of the handkerchief is tucked into a pocket with the fold line at 50 the pocket opening and the body portion adjacent the fold line depending from the fold line into the pocket, said flap will depend by reason of its weight alone from the fold line downwardly and will lie smoothly 55 against the outside of the pocket.

55 In testimony whereof, I affix my signature.

GENEVIEVE H. MYERS.
